DIRECTIVE TRANSMISSION OF ENERGY

Filed Dec. 15, 1924

FIG. 1.

FIG. 2.

INVENTOR.
Ross Gunn

BY *Robert A. Young*
ATTORNEY.

UNITED STATES PATENT OFFICE

ROSS GUNN, OF NEW HAVEN, CONNECTICUT

DIRECTIVE TRANSMISSION OF ENERGY

Application filed December 15, 1924. Serial No. 755,985.

This invention relates to wireless directive transmission systems, and the primary object is the provision in a system of this kind of means for combining two directive radiating transmitters, transmitting at different frequencies, so as to produce a directive beat. The intensity of this beat frequency is proportional to the product of the two radio amplitudes.

With the above and other more detailed objects in view, as will be set forth as the description of my invention proceeds, reference is made to the attached drawing, in which

Fig. 1 is a diagrammatic view of the two oscillating directive circuits, and

Fig. 2 is a diagram of the signal energy curve.

A number of various systems have been known for the directive transmission of signals, as for example that set forth in Patent 1,379,541, where signals are directly propagated from the source in pairs of quickly succeeding individual signals at small time intervals, the signal of each pair being in different directions, not only from each other but also from the corresponding individual signals of the preceding pair of signals, and of the succeeding pair.

In the arrangement as will be set forth in my invention the idea involved depends on the fact that two oscillatory waves of different radio frequencies will produce difference for beat frequencies, which are proportional

to the product of the two radio amplitudes when properly rectified at the receiver. This basic idea may be used with any standard directive system, and in the example set forth in the figures, two loops 1 and 2 are shown

connected to circuits 3 and 4 respectively. Circuit 3 is inductively coupled to a second circuit 5 which is adapted to transmit or produce continuous waves of a wave length of 1000 meters. Circuit 4 is inductively coupled to a circuit 6, which is adapted to emit continuous waves of a wave length of for example 997 meters. A wave trap 7 is inserted in circuit 3 so as to cut out frequencies generated in circuit 6, and a second wave trap 8 is

inserted in circuit 4 so as to cut out frequen-

cies generated in circuit 3. A key 9 is included in circuit 6 so as to interrupt this circuit when so desired.

The two loops which form two directive radiating transmitters are mounted so as to be positioned about 45° apart in azimuth.

If the two signals are sent out, that is, a signal of 997 meters as continuous waves in circuit 4 and signals of 1000 meters as continuous waves in circuit 3, the effect of the relative positioning of the two loops and the directional characteristics of these two loops will be of directive transmission of a beat note, which in the instance indicated would be at about 1000 cycles and hence audible in a telephone of a listener located at the point 10 of Figure 2. Since the beat note is of an intensity proportional to the product of the two radio amplitudes, the beat note may be distinguishable for a great distance as compared to a signal generated in the customary manner, but will diminish to zero intensity whenever the intensity of the signal from either directive transmitter becomes zero. The key or interrupter 9 in circuit 6 is provided so that one of the two radio signals may be stopped to cause a dropping of the beat signal to zero, regardless of the intensity of the other radiated signal. The beats produced may be of an audible frequency, or they may be of sub or super audible, or of radio frequency, and may be used as direct indicators or as carriers of signals, impulses or speech.

The signal energy curve for the example cited in the foregoing is shown in Fig. 2, and is in the shape of two elongated loops 11 and 12, extending radially 180° apart from a central point, and also the two small loops spaced 90° from the larger loops radiating from the central point which is the point from which the signals are transmitted. The energy distribution curve therefore looks something like a four-leaf clover instead of two circles as either loop alone would give.

An important case of the invention just set forth would be where the beat frequency of the continuous waves is exactly equal to the modulation frequency superimposed on the main generated frequency.

I am aware that various modifications may be made of the beat example which I have used for purposes of illustration of my invention.

5 I claim:

1. A wireless directive transmission system, the combination of a plurality of radiating directive transmitters adapted to radiate directionally in different directions, means 10 for emitting continuous waves from one directive transmitter at a definite frequency, means for simultaneously emitting continuous waves from the second directive transmitter at a slightly different frequency, and 15 means for modulating one of said means.
2. A wireless directive transmission system, comprising in combination, a plurality of radiating directive transmitters, means for emitting continuous waves from one directive 20 transmitter at a definite frequency, means for simultaneously emitting continuous waves from the second directive transmitter at a slightly different frequency, and means for modulating one of said means so that the combined effect of said means and said transmitters is to produce a radiated directional beat 25 note of audio frequency, the beat frequency being equal to the modulation frequency superposed on the main generator frequency.

30 In testimony whereof I affix my signature.

ROSS GUNN.
